CLAIM

The ornamental design for a shoe upper, as shown and described.

DESCRIPTION

FIG. 1 is a top left front perspective view the shoe upper showing our new design;

FIG. 2 is a left side elevational view thereof;

FIG. 3 is a right side elevational view thereof;

FIG. 4 is a top plan view thereof;

FIG. 5 is a front elevational view thereof; and,

FIG. 6 is a back elevational view thereof.

The purpose of broken lines in the drawings is to illustrate environmental structure and/or boundaries that form no part of the design to be patented.

1 Claim, 5 Drawing Sheets
